UNITED STATES PATENT OFFICE.

CHARLES H. TOMLINSON, OF MANSFIELD, OHIO, ASSIGNOR, BY MESNE ASSIGNMENTS,
TO THE TOMLINSON COUPLER COMPANY, OF MANSFIELD, OHIO, A CORPORATION
OF OHIO.

ELECTRIC COUPLING.

1,422,905.

Specification of Letters Patent. Patented July 18, 1922.

Application filed June 22, 1912, Serial No. 705,149. Renewed November 15, 1920. Serial No. 424,253.

To all whom it may concern:

Be it known that I, CHARLES H. TOMLINSON, a citizen of the United States, residing at Mansfield, in the county of Richland and State of Ohio, have invented certain new and useful Improvements in Electric Couplings, of which the following is a specification.

This invention relates to an electric coupler, and is more particularly designated and described as a multiple circuit connector, adapted to be used in connecting a plurality of separate and distinct circuits, such, for example, as the several circuits of a multiple control system for electric cars and trains. The principal object of the invention is to provide an improved, simple device of this class which is effective and efficient in operation.

More particularly the object of the invention is to improve the several features of construction, whereby connections may be made in a more satisfactory and efficient manner, and to construct a casing which may be more readily fitted and adapted to conform to various installations, and which may be more readily aligned and connected with a co-operating device of the same kind.

For the attainment of these ends, and the accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings Figure 1 is a longitudinal section of a pair of couplers constructed in accordance with the principles of my invention and applied to car couplers, connections also being shown to a fluid pressure control pipe line of the cars; Fig. 2 is an end view of one of the couplers removed from the car coupler with the door swung to open position; Fig. 3 is a side elevation of one of the couplers with the door swung to open position; Fig. 4 is a diagrammatic representation of the electrical connections of the present embodiment of the invention; Fig. 5 is a plan view of a pair of couplers in abutting position, parts being shown in section; Fig. 6 is a perspective view of one of the electrical connectors of the connector block; Fig. 7 is a representative view

of one of the contact strips of the insulating blocks.

This invention is similar in function and operation to the applicant's co-pending application for an electrical multiple connection plug, filed in the United States Patent Office on or about April 17, 1912, Serial Number 691,511.

It has been found in practice that certain difficulties arise in devices of the class to which this invention relates when a number of separate connecting points are to be connected with a number of separate receiving sockets or openings, and the present invention is adapted to overcome these objections by providing a single movable member in connection with each of the plugs which carries contact connectors for each of the separate circuit connections. In addition to this, it is found more feasible in practice to construct the coupler with a round or cylindrical casing.

Referring now more particularly to the drawings, and in the present exemplification of the invention, the numeral 10 designates generally a car coupler preferably of any well known self-aligning type, to which an electric coupler is connected. Although the couplers are used in pairs, they depend for their successful operation upon their similarity of construction, and therefore the description of one coupler will answer for any number.

This coupler is preferably formed with a cylindrical casing 11, substantially round in cross section and having extending perforated lugs 12, by means of which the coupler is suspended from the car coupler 10.

The car coupler is formed with perforated lugs 13 and a bolt 14 extends through the perforation in the lugs 12 and 13, and through a downwardly projecting portion 15 of the car coupler 10 to hold the electric coupler in position. The lugs 12 are spaced apart a distance less than the distance of the lug 13 from the supporting portion 15 of the car coupler, and a spring 16 is disposed between the lugs 12 and 13, tending to press the face of the electric coupler in advance of the face of the car coupler.

The casing 11 is formed at the forward end with diametrically opposite perforated ears 17, in one of which is disposed an aligning pin 18. This aligning pin 18 has a head shaped portion 19 with a conical

tip 20, the head shaped portion being preferably larger than the perforation in the ear to which it is attached, and the perforation in the other ear 17 being large enough 5 to receive the head 19 of the pin and to hold it firmly in position. The conical tips of the pins assist in alining the couplers.

Projecting from the outside of the casing 11, and preferably opposite the supporting 10 lugs 12 are perforated lugs 21 in which a door 22 is pivotally mounted by means of a pin 23 which extends through the lugs. Disposed between the lugs 21 and surrounding the pin 23 is a coil spring 24, which is 15 adapted to bear against the door 22, tending to press it in a closed position over the face of the coupler.

The rear of the casing 11 is provided with a plate 25, having an outward cylindrical 20 projection 26, with a perforation 27 forming communication between the cylindrical portion and the interior of the casing 11. This plate 25 is also provided with openings 28, through which cables or conductors for the 25 electrical connections may be inserted. These conductors are omitted from the present application, as they do not concern the invention. The cylindrical portion 26 is disposed at a distance from the center of the plate 30 from a vertical center line, but is preferably in the horizontal center as viewed from the side. (See Figs. 5 and 1.) A web 28' depends from the cylindrical portion 26, forming means for pivotally mounting the 35 latch 29. The door 22 is provided with an opening 30 adjacent its upper end, and the latch 29 is formed with a hooked shaped portion 31, whose end is adapted to engage in the opening 30 to hold the door in its 40 turned back position.

Disposed in the cylindrical portion 26 is a piston 32, to which is connected a piston rod 33, extending through the opening 27 into the casing 11, and a spring 34 is disposed 45 about the piston rod 33, tending to press the piston outwardly from the casing 11. At the outer end of the cylindrical portion 26 is a removable cap 35, having an opening to admit fluid under pressure. A 50 fluid pressure pipe 36 is commonly provided in connection with cars to operate and control the brakes or other fluid pressure devices which are provided with cocks 37 to control the admission of pressure to an adjacent cock. A flexible hose 38 is connected 55 to the pipe 36 between the cock 37 and the end of the line, and to the cap 35 of the cylinder 26. Another cock 39 is provided between the cock 37 and the adjacent end 60 of the pressure pipe 36 to permit fluid under pressure to be exhausted from the cylinder 26 when the cock 37 is closed and the pipes 36 are still connected at the ends.

In the forward inner edge of the casing 11 65 is a groove 40, preferably beveled inwardly,

and disposed in the groove is suitable packing material 41 which preferably projects slightly from the face of the coupler (see Fig. 3), so that it will be engaged and compressed by the door 22 in closing to form 70

substantially tight connections. Extending inwardly and spaced from the face of the coupler are perforated lugs 42, and disposed in the end of the coupler against the lugs 75 is an insulating block. This block is preferably composed of separate portions or members 43, 44, which extend outwardly from the lugs 42 substantially flush with the outer face of the coupler, thereby retaining the packing 41 securely in position. This 80 block of insulating material is secured in position in any desired or suitable manner, such, for example, as by means of bolts 45, having counter sunk heads in the face of the insulating block, and extending through 85 the perforations in the lugs 42, the ends of the bolts being threaded to receive the nuts 46. In this manner the separate members of which the block is composed are held firmly together, and the entire block is held 90 securely in place in the casing. The insulating block is formed with openings 47 symmetrically disposed with respect to each other and to a vertical center line, and each being a counterpart of the other, so that 95 when the blocks are placed face to face, the openings will exactly correspond and register. The sides of the openings 47 are formed with grooves 48, of any desired width and depth, and extending through the openings 100 from side to side. These grooves are preferably of a size to contain contact strips which are secured to the block, and may be for contact strips of the same size or for different sizes. In the present exemplification 105

of the invention the grooves 48 on one side of each of the openings 47 are of the same size, and on the other side of each opening is a groove 48' wider than the others, which is adapted to receive a wider contact strip 110 or member. It will be noted that the outer edges of the openings 47 are preferably rounded, so that the openings will conform more nearly to the opening in the casing. The shape of the openings, however, may be 115 varied to correspond with the size of the casing, and it is contemplated that if the casing is large enough, a plurality of openings may be disposed upon each side of the vertical center line of the casing. It is also 120 contemplated that any number of contact grooves may be provided along the edges of the openings through the insulating block, and they may be of any desired width to receive the contact members corresponding thereto. Different installations of the couplers will require different numbers of contact strips corresponding to the service to 125 be rendered.

The contact strips on one side of each of 130

the openings 47 are formed by bending a strip of conducting material 49 substantially at right angles, and disposing one end of the member in one of the grooves 48, with the 5 end extending inwardly in the coupler and the other end disposed between the block members 43 and 44. A connecting pin is secured to the end of the member 49, which is disposed between the block members and 10 extends to the inside face of the block 43, where it forms a terminal for electrical connection to the contact strip 49. This contact strip is preferably of spring material, and is so bent that the end disposed in the 15 groove 48 is pressed outwardly therefrom, so that a good electrical contact is made with a slidable member, as hereinafter set forth. In the present exemplification of the invention a wider contact strip 50 is provided, 20 which is connected in the insulating block and similarly disposed with respect thereto, as it is adapted to form a main or bus line contactor.

In the present exemplification of the invention the grooves 48 of the adjacent openings 47 disposed on opposite sides of a vertical center line are provided with a common contact strip 51, which is bent over the partition connecting the openings between the 25 block members 43 and 44, with their ends disposed in the opposite grooves 48. (See Figs. 5 and 7.) A pin 52 is connected to the edge of one of the contact strips 51 and extends through the block 43 to the inside 30 face thereof, where it forms a terminal for electrical connection with the strip.

The corresponding contacts in both openings are preferably connected so that the contacts of each opening are connected with 40 the corresponding contacts of the other openings. A diagrammatic representation of this connection is shown by Fig. 4, from which it will be seen that the contacts 49 and 50 for each of the openings are provided 45 with a common connection and contact strips 51 which extend into both openings 47 and require only a single terminal connection.

In order to connect the corresponding contact strips of adjacent couplers, a movable 50 block 52 is provided, which is secured to the piston rod 33, which extends through the opening 27 in the plate 25. The cylindrical portion 26 is disposed substantially in alignment with one of the openings 47, 55 through the insulating block in the face of each coupler, so that the connector block 52 may be moved in accordance with the movement of the piston and the piston rod through the connector block of the coupler, 60 and into a corresponding opening 47 in an adjacent coupler. For this purpose it is necessary that the block 52 be provided with a movable conductor of sufficient length to form connections between the contact strips 65 in the face of one coupler and the contact

strips in the face of the adjacent coupler, and the casing must be sufficiently long to contain the block 52, when it is retracted, so that no portion of it will protrude beyond the face of its coupler. This connector block 70 52 is provided with a plurality of connecting bars 53, which project slightly from the lateral faces of the block and are of such a width that they will enter the grooves 48 in the sides of the openings 47 to make frictional connection with the contact strips 49. These bars 53 are preferably rounded at the 75 ends, as at 54 (see Fig. 6), and are formed with perforations 55 through which pins 56 may be inserted to connect the bars in the 80 block 52. Any other suitable method of connecting the bars to the block may be employed, as long as they are firmly connected thereto. A wider contact strip or member 57 (see Fig. 1) is provided, which is secured 85 to the face of the block in any suitable manner, as for example, by means of screws. This contact member 57 is disposed to contact with the contact strip 50 in the insulating block.

The forward end of the insulating block 52 is preferably formed with beveled or rounded edges 58, by means of which the blocks may enter the corresponding opening in an adjacent coupler more easily. It is 90 evident that since each coupler is provided with but a single connector block 52, the connections from the counterpart openings must be symmetrical in order that the electrical connections may still be made between 95 the contacts of the adjacent couplers, even if only one of the connector blocks is projected from one coupler into the other. It is contemplated, however, that in actual operation the connector blocks of both couplers 100 will be moved in position with the other coupler, so that all of the contact connections may be insured. This is a connection protected against the breaking or dislocation of one of the contact members in one of the 105 openings.

To operate the connector blocks whereby they will be moved in connection with the contact strips of an adjacent coupler, it is necessary only to open the cock 37 in the 110 pressure line 36, whereupon the fluid pressure will be exerted upon the piston 32, causing the block 52 to be projected through the opening in an adjacent coupler against the pressure of the spring 34. When the pressure lines of two cars are connected, it is necessary only to open the cock of one of the 115 cars in order to operate both of the connecting blocks 52. In order to retract the blocks 52 the cock 37 is closed, and the release cock 120 39 is opened, whereupon the fluid pressure behind the pistons 32 will be released and the blocks will be driven inwardly by the action of the springs 33.

It will be noted that the outer end of the 125

4

blocks 52 are not provided with conductors, so that contact must be made with the sides of the block in order to cross circuit connections. Also the block member 44 is disposed 5 over the ends of the contact strips so that it is necessary to have a connecting bar 53 some distance within the openings 47 in order to form electrical connections between the corresponding strips. This is a connection protected 10 against short-circuiting, and even with the door 22 in open position, there is little danger of difficulty arising from the short-circuiting of the connections. By having a single connector block for each of 15 the couplers, there is no danger of one of the connectors becoming bent and thereby preventing the connector block from being inserted within the corresponding opening. The action of the connector blocks 52 is 20 direct, since they are disposed directly in line with the piston rod and will receive the full pressure applied to the piston.

While I have thus described the preferred embodiment of my invention, it is evident 25 that those skilled in the arts to which this relates may make various changes in the construction, combination and arrangement of the several parts without departing from the spirit and scope of my invention.

30 What I claim is:—

1. In an electric coupler, the combination with a casing open at the forward end, of a door hinged below the casing at the forward end with an opening through the door at its 35 outer edge, and a latch pivoted on the casing at the other edge with a hooked end to pass under the door and to engage in the opening at the outer end of the door to hold the door in open position and to prevent its disengagement.

2. In an electric coupler a casing formed at the outer end with an undercut groove, a yielding packing material held therein by the groove and adapted to project slightly 45 from the end of the casing, and a spring-pressed door moving in a position over the end of the casing in contact with the packing to compress it to form thereby a watertight joint for the casing.

3. In a multiple electric coupler, the combination with an open casing formed with inwardly projecting perforated lugs spaced from the open end thereof, and a groove undercut with respect to the face of the casing, 55 yielding packing material disposed in the groove and extending from the open end thereof, an insulating block disposed in the open end against the said lugs and in contact with inner edge of the packing material to 60 hold it in the said groove, and means for securing the insulating block within the open end of the casing.

4. In an electric coupler adapted to be used with a counterpart coupler, fixed contacts therein, a connector comprising a block

of insulating material and a plurality of separate insulated conducting members each secured to and projecting from the side of the block beginning at a distance from the end thereof and of a length to extend from 70 the contact of one coupler into an adjacent counterpart coupler and there to make electrical connection with its corresponding fixed contact.

5. In an electric coupler adapted to co-operate with an opposite counterpart coupler, a fixed contact therein, a connector comprising a movable block of insulating material with beveled front edges, and strips of conducting material terminating short of the 80 end of the block and fixedly secured to the sides of the block and projecting therefrom, the side portions of the strips being of sufficient length when moved to make electrical connection between the fixed contacts of two 85 adjacent couplers.

6. In an electric coupler, the combination with a casing open at one end, of a block of insulating material disposed in the end of the casing having counterpart openings, and 90 parallel slots in the sides of the openings and contact members secured to the block each of which lies in a slot in two of the openings.

7. In an electric coupler, the combination with a casing open at one end, of a block of 95 insulating material disposed in the end of the casing having two counterpart openings with parallel slots extending through the block at the sides of the opening, and spring contact strips secured to the sides of the slots 100 in the block and connected with strips in the counterpart opening to make double connections.

8. In an electric coupler, the combination with a casing open at one end, of a block of 105 insulating material disposed in the end of the casing having openings symmetrical with respect to a center line, and contact strips extending over a partition between adjacent openings and disposed with the ends in both 110 openings at the sides thereof.

9. In an electric coupler, the combination with a casing open at one end, of a block of insulating material disposed in the end of the casing having symetrically disposed 115 openings, and contact members secured to a partition between adjacent openings with the ends extending from the sides of both openings.

10. An electric coupler adapted to be used 120 with a counterpart coupler comprising a block of insulating material having symmetrically disposed openings, a plurality of contact strips secured to the block in each opening, and slidable conductors to contact with the several strips to connect the strips in the opening of one block with opposite symmetrically disposed strips in another symmetrically disposed opening in the adjacent or opposite block.

11. An electric coupler adapted to be used with a counterpart coupler comprising a block of insulating material having symmetrically disposed openings, a plurality of 5 corresponding contact strips secured to the block and disposed in each opening, and an insulating connector block movable through one of the openings in the insulating material and having electrical conductors which 10 contact at all times with the said strips of its coupler and movable with the block to form electrical connections with corresponding contact strips of an adjacent coupler. 12. In an electric coupler, the combination 15 with a casing open at one end, of a block of insulating material disposed in the end of the casing having symmetrically disposed openings, a plurality of contact strips secured to the block and disposed in each 20 opening, and an insulating connector block greater in length than the thickness of the insulating material having conductors which contact with said strips to form electrical connections, disposed in and movable through 25 the openings to contact with corresponding strips in an adjacent coupler to form electrical connections. 13. In an electric coupler having a casing with aligning means and adapted to co- 30 operate with a counterpart coupler, the combination with insulating blocks disposed in the end of the coupler having counterpart openings, of contact strips disposed in the openings at the sides thereof, an insulating 35 connector block movable through the opening of one insulating block into the corresponding opening of an adjacent aligned coupler, and conductors disposed on the sides of the connector block contacting with the said 40 contact strips in the openings to complete electrical connections between the couplers. 14. An electric coupler adapted to cooperate with a counterpart coupler comprising an insulating block having counterpart 45 openings therethrough, electrical contacting members in the openings each connected to a corresponding contact member in each one of the counterpart openings, a connector block movable only in one of said openings, 50 electrical connectors in contact with said members and of a length to remain in contact when the said block is moved outwardly from one coupler and into another one, the other coupler having a correspondingly movable 55 connector block whereby two connections are made for each coupler, and means to move the said connector block. 15. In an electrical coupler, the combination 60 with a casing open at one end, an insulating block disposed in the open end and having counterpart openings therethrough, electrical contact members in the openings, a connector block movable in said openings, electrical connectors in contact with said 65 strips and of a length to remain in contact when the said block is moved outwardly from the coupler, a device to move the connector block outwardly, and resilient means to oppose the action of the device and to retract the block. 70 16. In an electrical coupler, a casing open at one end, a block of insulating material disposed in the open end and comprising a plurality of separate members connected together, and having counterpart openings 75 therethrough, and contact strips folded over the partition between adjacent openings between the members of the said block with the ends extending from the sides of said openings. 80 17. In an electrical coupler, a casing open at one end, a block of insulating material disposed in the open end and comprising a plurality of separate members connected together, and having counterpart openings 85 therethrough, contact strips folded over the partition between adjacent openings between the members of the said block with the ends extending from the sides of said openings, and means extending from the said contact 90 strips to the under side of the block constituting electrical terminals therefor. 18. In an electrical coupler, a casing open at one end, a block of insulating material disposed in the open end and comprising a 95 plurality of separate members connected together, and having counterpart openings therethrough, contact strips connected to the blocks and disposed at one side in the openings, other contact strips folded over the 100 partition between adjacent openings between the members of said block with the ends extending from the other side in the openings, means connected to the strips extending through the block to the back thereof and 105 constituting electric terminals therefor, and conductors to connect the corresponding first mentioned contact strips in the counterpart openings. 19. An electric coupler adapted to cooperate with a counterpart coupler, comprising a casing, a block of insulating material disposed in the end of the casing having symmetrically disposed openings, a plurality of 110 contact strips secured to the block in each opening, and an insulated connector block having conductors which contact with said strips to form electrical connections disposed in and movable through the openings of one block into a corresponding symmetrical 115 opening of an opposite block, so that a double block connection is made between two 120 double block connection is made between two 125 cooperating couplers. 20. An electric coupler adapted to cooperate with a counterpart coupler, comprising a 125 casing, a block of insulating material disposed in the end of the casing having symmetrically disposed openings, a plurality of contact strips secured to the block in each opening, an insulated connector block hav- 130

ing conductors which contact with said strips to form electrical connections disposed in and movable through the openings of one block into a corresponding symmetrical 5 opening of an opposite block so that a double block connection is made between two cooperating couplers, and means mounted on said casing to advance and retract said connector block from the opening of the opposite 10 coupler.

21. An electric multiple coupler adapted to be used with a counterpart coupler each of which is formed with a casing having a reduced portion at one end, a connector 15 movable in the casing, electrical connection bars carried by the connector, and a piston movable in the reduced portion and connected to the connector for moving it from its casing into and out of the casing of an adjacent 20 coupler.

22. An electric coupler adapted to cooperate with a counterpart coupler, comprising a casing, insulating material disposed within the casing having symmetrically disposed 25 contacts, and an insulated connector block having conductors thereon which are adapted to make connection with said contacts and movable from one coupler into an adjacent coupler so that a double connection is made 30 between contacts of two cooperating couplers.

23. An electric coupler adapted to cooperate with a counterpart coupler comprising a casing, insulating material therein with contacts symmetrically disposed on opposite sides of a vertical center line, an insulated connector block having conductors which are adapted to make connection with said contacts within the casing and is movable from 35 the casing of one coupler to make connection with the contacts of an adjacent coupler on one side of the vertical center line so that a double connection is made by the two connector blocks between two cooperating 40 couplers, and means in connection with each cas- 45 pler.

ing to advance and retard said connector block from the opening of the opposite coupler.

24. In a coupling for electric train line circuits, the combination with a casing 50 adapted to be supported at the end of a car, and containing a plurality of contact fingers connected to the respective circuits, of a movable carrier with contact bars for connecting said contact fingers with the corresponding contacts of a counterpart coupler on the adjacent car, a piston for actuating said carrier, and a valve for controlling the supply of fluid pressure to said piston.

25. In a coupling for electric train line 55 circuits, the combination of a casing, fixed contact fingers mounted therein and connected to the respective circuits, a movable contact carrier normally held out of operative position, and a fluid pressure mechanism for shifting said contact carrier to its operative position to establish electrical connection between said fixed contacts and the corresponding fixed contacts of an adjacent car.

26. In an electrical coupling mechanism 70 for cars, the combination of a casing adapted to be supported upon the end of a car, a movable contact carrier mounted in a normally inoperative position in said casing, a movable member operatively connected to 75 said carrier, contact fingers mounted in said casing and connected to the respective train line circuits, and means for actuating said movable member to shift the contact carrier to its operative position to establish electrical 80 connection with the contacts of a counterpart coupling mechanism on an adjacent car.

In testimony whereof I have signed my name to this specification, in the presence of two subscribing witnesses, on this 19 day of 85 June A. D. 1912.

CHARLES H. TOMLINSON.
